UNITED STATES PATENT OFFICE.

ROBERT CRAIG GREENE, OF WASHINGTON, DISTRICT OF COLUMBIA.

CUFF HOLDER.

Application filed June 29, 1922. Serial No. 571,634.

To all whom it may concern:

Be it known that I, ROBERT CRAIG GREENE, a citizen of the United States, and resident of Washington, in the District of Columbia, 5 have invented certain new and useful Improvements in Cuff Holders, of which the following is a specification, reference being had therein to the accompanying drawing.

It is at present customary to provide 10 shirts with permanently attached cuffs, and practically the use of such shirts is compulsory since the makers put no others on the market. Attached cuffs are pleasing to many, but both hand and brain workers find 15 that, especially in summer, cuffs that cannot be removed are necessarily soiled soon after work is begun, and also find that, incidentally, laundry bills are materially increased, although soiled cuffs are worn for the 20 greater part of each day.

For such reasons, it is common to reverse or turn back attached cuffs, holding them by various expedients, none of which are satisfactory.

25 The object of this invention is to provide for reversing the cuffs and restoring them to normal condition as often as desired, quickly and without rumpling them, or preventing them from being moved upwardly upon the 30 arm as far as may be wished. These results are accomplished by using novel simple attachments with common cuff studs.

In the accompanying drawings,

Fig. 1 is a plan view of a cuff after reversal and provided with my devices.

Fig. 2 is a side view of the same devices, certain chain connected snap buttons being shown, in diametrical section, slightly above corresponding parts of a separable cuff stud and ready for engagement therewith.

40 Fig. 3 shows two pairs of chain-connected buttons, detachably united to form a closed loop, which may be secured in any button-hole or on a key ring, for example, so that these members are always available for use.

In these figures, A, A' represent parts of 45 a two part cuff-stud, one part being formed with a head D, of usual form, to engage in a recess E of the companion part. These parts are usually inserted, respectively, in buttonholes in the cuff and are engaged with

and disengaged from each other, like the parts of a glove fastener, without removing them from the buttonholes. When they have been disengaged and the cuff has 55 been reversed, each part is engaged by a snap button B, or B', one adapted to engage the head D and the other to enter the recess E, since the head and recess of the buttons are substantial duplicates of the head and recess of the parts of the stud. The meeting faces of the stud part and the corresponding button are convex, or rounded from each other so that a marginal crevice is formed, facilitating disengagement and giving space 60 for the terminal link of a short chain C which permanently connects the two buttons.

The buttons B, B' may be externally ornamented, so that when in use with reversed cuffs they appear like cuff studs connected 65 by a chain.

It may be noted that the chain connecting the sides of the cuff allows such separation as permits the cuff to move upward over the forearm, if desired, although the 70 cuff when its margins overlap, as in the ordinary use of the stud, does not permit such movement.

What I claim is:—

1. The combination with apparel portions 80 to be connected, of companion snap fastener parts secured to said portions, respectively, and a chain having at one end a snap fastener member adapted to engage one of said parts and at the opposite end a companion snap fastener member adapted to engage the other of said parts.

2. The combination with a two-part cuff stud of the snap fastener type, of a short chain having terminal snap buttons adapted 85 for detachably engaging corresponding members of the two part stud.

3. The combination with the parts of a cuff stud of the snap fastener type, of a short chain carrying terminal snap buttons 90 adapted to engage each other and also to engage the corresponding members, respectively, of the cuff stud.

4. The combination with the co-acting members of a two part stud of the snap 100 fastener type, of two snap buttons adapted to engage, respectively, said members while

extending from their planes to leave between the margins of the two space for attaching a chain, and a short chain connecting the marginal portions of said buttons.

5 5. The combination with a cuff stud of a separable type, of a tie member having buttons with separable fasteners adapted to en-

gage, respectively, the members of the cuff stud, and a flexible connection restricting the separation of said buttons.

In testimony whereof I hereunto affix my signature.

ROBERT CRAIG GREENE.
